UNITED STATES PATENT OFFICE.

THOMAS S. COOPER, OF CHARLESTON, WEST VIRGINIA, ASSIGNOR TO KOOPER DAMPER CO., A CORPORATION OF DELAWARE

AUTOMATIC DAMPER.

1,370,785.

Specification of Letters Patent.

Patented Mar. 8, 1921.

Application filed November 13, 1919. Serial No. 337,818.

To all whom it may concern:

Be it known that I, THOMAS S. COOPER, a citizen of the United States, residing at Charleston, in the county of Kanawha and 5 State of West Virginia, have invented certain new and useful Improvements in Automatic Dampers; and I do declare the following to be a full, clear, and exact description of the invention, such as will enable others 10 skilled in the art to which it appertains to make and use the same.

This invention relates generally to dampers, but more particularly to automatic dampers.

15 One object of the invention is to provide a damper to be placed in a smoke pipe with novel thermostatic means for controlling the position of the damper according to the temperature of the products of combustion 20 passing through the smoke pipe.

Another object of the invention is to provide a thermostatically operated damper which can be easily applied to smoke pipes without specially adapting the smoke pipes 25 for the reception of the damper, and one which will be of extremely simple construction, efficient and reliable in operation, and well adapted to the purpose for which it is designed.

30 With these and other objects in view, the invention consists of the novel features of construction, and the combination and arrangement of parts as will be hereinafter fully described and claimed.

35 The invention may be carried out in several ways, but in the accompanying drawings the preferred constructions are shown.

In the drawings,

Figure 1 is a horizontal sectional view 40 through a horizontal smoke pipe, showing a thermostatic damper constructed in accordance with this invention disposed therein, the damper being in open position;

Fig. 2 is a vertical sectional view through 45 the smoke pipe, taken on the line 2—2 of Fig. 1;

Fig. 3 is a transverse sectional view taken on the line 3—3 of Fig. 2;

Fig. 4 is a perspective view of a portion 50 of the shaft on which the damper is movably mounted and showing more particularly the shape of the cam;

Fig. 5 is a vertical sectional view through 55 a vertical smoke pipe, showing a slightly different type of damper mounted therein;

Fig. 6 is a vertical sectional view taken on the plane indicated by the line 6—6 of Fig. 5; and,

Fig. 7 is a perspective view of a portion 60 of the sleeve which connects adjacent sections of the smoke pipe together, and a portion of the shaft upon which the damper is mounted.

In the drawings above briefly described like parts are indicated by similar reference 65 numerals throughout the various views, the numeral 1 designating a sleeve which is adapted to be disposed within the adjacent ends of a pair of adjacent smoke pipe sections A and B to hold these sections together. The ends of the sections A and B abut against a ridge 2 formed on the outside 70 of the sleeve 1 intermediate of the length of the same.

Extending transversely through the sleeve 75 1 and ridge 2 at diametrically opposite points are openings 3, and formed in the ridge 2 adjacent one of these openings is a notch 4. Extending through the openings 3 is a shaft 5 carrying at one end a head 6 between which and the outer side of the smoke pipe sections A and B and sleeve 1 is disposed a coiled spring 7, while its other end carries a transversely extending pin 8 adapted to be held in contact with the sleeve 80 1 in the notch 4 by the coiled spring 7, and also a handle 9.

The shaft 5 is formed at its intermediate portion at a preferably central point in the smoke pipe with a cam 10. This cam 10, as 90 shown, is altogether flat on one side while its other side is flat at its intermediate portion and beveled at its edges as clearly shown in the drawings.

The numeral 11 designates a damper 95 which is of circular shape to conform to the cross sectional configuration of the smoke pipe, and which is provided on a diametrical line with oppositely arranged offset or curved strips 12 by which the damper is 100 movably mounted at its intermediate portion upon the shaft 5, said strips 12 being disposed on opposite sides of said shaft. The damper 11 is provided with an elongated opening 13, and disposed adjacent or 105 substantially over this opening is a thermostatic bar 14, the latter being secured at one of its ends by securing elements 15 or in any suitable manner to the damper 11 while its other end bears against the cam 10. In the 110

form shown in Figs. 1 to 3 of the drawings the thermostatic bar 14 is composed of strips of dissimilar metals and is normally straight. In this condition it exerts sufficient pressure 5 against the cam 10 that its free end will bear against the flat portion of the cam rather than one of its beveled edges and thus hold the damper 11 in a horizontal and opened position. When in this position as the products 10 of combustion passing through the smoke pipe strike against the damper and the thermostatic bar, the latter will become heated and as the heat reaches a predetermined amount the bar 14 will bow or bend 15 owing to the unequal expansion of the dissimilar metals of which it is composed. This distortion of the bar 14 relieves its pressure upon the cam 10 so that the weight of the heavier side of the damper 11 causes 20 the latter to swing into a partially closed position as indicated by the dotted lines in Fig. 2. As the fire in the fire-box to which the smoke pipe is connected is checked and the temperature of the products of combustion 25 decreases, the bar 14 will straighten, thereby again exerting pressure upon the cam 10 and passing up its adjacent inclined edge until it altogether engages the flat portion of this side and consequently moving 30 the damper to opened position.

The smoke pipe shown in Figs. 1 to 3 of the drawings is a horizontal smoke pipe. In Figs. 5 and 6 a vertical smoke pipe is shown and the construction of the various parts of 35 the invention is the same as above described with the exception that the thermostat bar 14 is normally bowed or bent, and the cam 10 is disposed a small amount out of right angles with the damper 11 instead of parallel with the same, when said damper stands open, so that the bar 14 only exerts a slight pressure upon the inclined edge of the cam under normal conditions to allow the damper 40 to be disposed in vertical or open position. When the bar 14 becomes heated by the products of combustion passing through the smoke pipe it straightens, thereby increasing its pressure against the cam 10 and passing 45 from the inclined edge of the latter to the intermediate flat surface of the same to move the damper into a partially closed position as shown in the dotted lines in Fig. 6. After the bar 14 cools and it again assumes its curved configuration, the damper will 50 swing under its own weight to the vertical position.

The shaft 5 is turnably mounted in the openings 3 of the sleeve 1, and the handle

9 is for the purpose of turning it and adjusting it to any desired position. If the 60 thermostat becomes choked by soot or the like so that it will not operate effectively until cleaned, the damper may be operated manually by turning the handle 9.

From the foregoing description, taken in 65 connection with the accompanying drawings, the construction, use and operation of the device will be readily understood.

Various changes in form, proportion, and in the minor details of construction may be 70 resorted to without departing from the spirit of the invention as defined in the appended claims.

What is claimed is:

1. A device of the class described comprising 75 a relatively fixed shaft, a damper rockably mounted on said shaft, a thermostatic bar at an angle to the shaft and bendable under changes in temperature, said bar being secured at one end to said damper at a 80 point remote from said shaft, and means on said shaft coöperable with the free end of said thermostatic bar for controlling the rocking of the damper upon the shaft.

2. A device of the class described comprising 85 a relatively fixed shaft, a damper rockably mounted on said shaft, a thermostatic bar at an angle to the shaft and bendable under changes in temperature, said bar being secured at one end to said damper at a 90 point remote from said shaft, and a cam on said shaft coöperable with the free end of said bar to control the position of the damper, said cam having a flat side for contact with said bar when the damper is in one 95 position and being provided with a beveled edge laterally spaced from the shaft axis and over which said bar rides as the damper moves from one position to another.

3. A device of the class described comprising 100 a ring widened in the direction of its axis for reception in the meeting ends of two smoke pipe sections, said ring having an external circumferential rib to abut the pipe sections and diametrically alined openings 105 extending through said rib, the latter having a notch at the side of one opening, a shaft passing through said opening and having a lateral projection normally received in said notch to prevent rotation, a damper in said ring rockably mounted on said shaft, and thermostatic means for controlling the rocking of said damper on the shaft.

In testimony whereof I have hereunto set my hand.

THOMAS S. COOPER.
